DISPLAY CONTAINER

Champe S. Andrews, North Chattanooga, Tenn.,
assignor to Box Blank Corporation, New York,
N. Y., a corporation of Delaware

Original application November 17, 1931, Serial
No. 575,519. Divided and this application April
12, 1933, Serial No. 665,664

3 Claims. (Cl. 229—34)

This invention relates to a display container and more particularly to a container having telescoping box and cover portions.

This application is a division of my copending 5 application, Serial Number 575,519, filed November 17, 1931.

In the display of certain merchandise it is often desirable to pack the material in such a manner that the top portion of the merchandise 10 will be raised above the side edges of the box so that when the cover is removed, the merchandise is clearly visible. Such low-sided boxes have found special favor, for example, in the packing of soaps, perfumes, powders and other merchandise which are in themselves attractive to the eye.

In order to properly cover merchandise which projects above the sides of the box, it is necessary to provide a cover member which telescopes 20 over both the top portion of the merchandise and the sides of the box. Some means should be provided to prevent the cover from becoming jammed down against the top of the goods to their injury and also to prevent the box or tray 25 from falling into the cover so as to make it difficult to separate the same.

An object of my invention is to provide a container comprising a box portion and a cover portion, the box portion having lower sides than the 30 cover portion, means being provided in the cover portion for limiting the extent to which the cover portion may be telescoped over the box portion, said means also providing a seat for the box portion for the display of merchandise.

Another object of my invention is to provide a 35 container useful for both shipping and display purposes, which is sturdy in construction, attractive in design and economical to manufacture and can be made entirely by machine operation.

The invention also consists in forming a product 40 having the general characteristics, the new and useful applications, and the several original features of utility hereinafter set forth and claimed.

Although the novel features which are believed 45 to be characteristic of this invention will be particularly pointed out in the claims appended hereto, the invention itself, as to its objects and advantages, and the manner in which it may be carried out, may be better understood by referring 50 to the following description taken in connection with the accompanying drawing forming a part thereof, in which:

Fig. 1 illustrates a blank from which the cover 55 portion of my container may be made;

Fig. 2 shows the cover portion and the box portion of my container as completely assembled;

Fig. 3 shows the box portion of my container 60 packed with merchandise, the merchandise projecting above the side walls thereof;

Fig. 4 is a longitudinal cross sectional view through the container, showing the relative position of the cover portion and box portion when the container is closed and merchandise packed therein, this view being taken on the line 4—4 of Fig. 5; 5

Fig. 5 is a vertical cross sectional view through the closed container taken on line 5—5 of Fig. 4; and

Fig. 6 is a longitudinal cross sectional view 10 through my container showing the box portion in display position within the cover portion.

Like reference characters denote like parts in the several figures of the drawing.

In the following description and in the claims, 15 various details will be identified by specific names for convenience, but they are intended to be as generic in their application as the art will permit.

The cover portion of my container is formed 20 from a single blank stamped into the shape shown in Fig. 1, and comprises generally a bottom wall portion 12, separated from the side wall portions 13 by score lines 14. The end walls 15 are separated from bottom portion 12 by score lines 16. 25 Tabs 17 are provided at each end of the side walls 13 and are separated therefrom by the score lines 18.

In assembling the container, the tab portions 17 may be secured by glue or cement to the inside 30 face of the end walls 15. Side flaps 19, separated from the side walls 13 by the score line 20, fold inwardly to form a lining for the side walls of the container. The end flaps 21, separated from the side end walls 15 by the score line 22, fold inwardly to form a lining for the end walls of the 35 container. Flaps 19 and 21 may be glued to the inside face of the respective side and end walls 13 and 15, if desired. Tongues 23 are provided which flare outwardly from each side edge of the 40 flaps 21 and are separated therefrom by the score line 24. It will be noted that the side edges 40 of the flaps 19 are mitered or beveled so that when the cover portion is fully assembled, the edges 45 will be spaced from the corners 18 of the cover portion. This permits assembly of the container automatically on a gluing machine. The edges 41 of the tongues 23 are also beveled, as clearly shown in Figures 1, 2 and 4. When the cover portion is completely assembled, as shown in Fig. 50 2, the tongues 23 will extend across the inside corners of the cover portion. The purpose of the tongues 23 will hereafter be described.

The box or tray portion of my container, as 55 shown in Fig. 2, may be made from a blank cut similar to the blank used to form the cover portion, except that the tongue portions 23 are left off. I do not limit myself, however, to this particular form of box, but any well known form of box portion may be used. The box portion com- 60

prises generally a bottom 25, side walls 26 and end walls 27.

It will be noted that the side and end walls 26 and 27 respectively of the box portion are of considerably less depth than the side and end walls 13 and 15 of the cover portion. The box portion is adapted to contain merchandise which may be so arranged as to extend considerably above the side and end walls, as clearly shown in Fig. 3.

When the cover portion, as shown in Fig. 2, is telescoped over the box portion, the extent of this telescoping movement is definitely limited by the tongues 23 which strike against the corners of the box portion and prevent further telescoping of the cover portion over the box portion. Due to the fact that the tongues 23 are slightly beveled along the edge 41, these tongues tend to bend, assuming a slightly curved form, and thus gives more contact area with the box bottom which rests against them. The tabs as thus arranged also exert a wedging and friction action against the box portion, thus holding it more securely in place.

The tongues 23 are preferably so arranged with respect to the side and end walls of the box portion that when the cover portion is completely telescoped thereover, the bottom wall 25 of the box portion will lie substantially flush with the edges of the side and end walls of the cover portion, as clearly shown in Figs. 4 and 5. The box portion can then be easily grasped to separate the same from the cover portion when the container is to be opened. The tongues 23, limiting the inward telescoping movement of the box portion, also prevents the cover portion from becoming jammed down upon the merchandise contained in the box portion. The merchandise is thus always fully protected within my container. The box portion can also be reversed with respect to the cover portion so that the bottom 25 of the box seats on the tongues 23, as shown in Fig. 6. In this position the cover portion serves as a pedestal for the box portion so as to attractively display the merchandise, a portion of which projects above the container.

It is now seen that I have provided a container, the box portion of which is adapted to contain and display goods which project above the enclosure walls thereof. Means are provided either in the cover portion or the box portion for preventing contact between the cover portion and the goods. The tongue portions 23, shown in Fig. 1, require very little material, are made at the time the blank is stamped, and they require no pasting or additional operation to position them in place, since they assume their proper position when the end flaps 21 are pasted against the inside face of the end wall 15. The box and cover portions can be assembled complete by automatic machinery. My novel container can be manufactured at a substantial saving in both labor and materials and is generally more economical to manufacture than display containers of this type heretofore devised.

While certain novel features of the invention have been disclosed and are pointed out in the annexed claims, it will be understood that various omissions, substitutions and changes may be made by those skilled in the art without departing from the spirit of the invention.

What is claimed is:

1. A container of the character described com-

prising a box member having enclosure walls, a cover member adapted for machine assembly having enclosure walls adapted to telescope over said box member, the enclosure walls of said cover member being of greater depth than the enclosure walls of said box member, opposite enclosure walls of said cover member each having an in-turned flap portion, the vertical edges of said in-turned flap portions being beveled and spaced from the adjacent closure walls, abutment pieces extending from the beveled edges of said flap portions across an inside corner of the cover member to limit the telescoped portion of said box and cover members when the container is in closed position and to provide a seat for the box member when in open display position, each of said abutment pieces having a slightly beveled top edge adapted to seat between the box portion and the cover whereby the cover is frictionally retained in position on the box portion.

2. A container of the character described comprising a box member having enclosure walls, a cover member adapted for machine assembly having enclosure walls adapted to telescope over said box member, the enclosure walls of said cover member being of greater depth than the enclosure walls of said box member, opposite enclosure walls of said cover member each having an in-turned flap portion, the vertical edges of said in-turned flap portions being beveled and spaced from the adjacent closure walls, abutment pieces extending from the beveled edges of said flap portions across the inside corners of the cover member to limit the telescoped position of said box and cover members when the container is in closed position and to provide a seat for the box member when in open display position, each of said abutment pieces having a slightly beveled top edge adapted to wedge between the box portion and the cover to frictionally retain the same in position on the box, the free ends of the abutment pieces assuming a slightly curvilinear contour when the container is in the closed position, whereby maximum area of contact between the abutments and the box member is obtained.

3. A container of the character described comprising a box member having enclosure walls, a cover member having enclosure walls adapted to telescope over said box member, the enclosure walls of said cover member being of greater depth than the enclosure walls of the box member, the end walls of said cover member each having an in-turned flap portion, the vertical edges of said in-turned flap portion being beveled and spaced from the adjacent closure walls, abutment pieces extending from the beveled edges of said flap portions across an inside corner of the cover member to limit the telescoped position of said box and cover member when the container is in the closed position and to provide a seat for the box member when in the open display position, the abutment pieces being hinged to the in-turned flap portions, the free ends of said pieces being adapted to assume a slightly curvilinear contour when the container is in the closed position, whereby maximum area of contact between the abutments and the box member is obtained, said abutment pieces having a slightly beveled top edge adapted to seat between the box portion and the cover to frictionally retain the cover in position on the box portion.
